(57) **CLAIM**

The ornamental design for a binocular casing, as shown.

DESCRIPTION

FIG. 1 is a top, front and side perspective view of a binocular casing showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the right of FIG. 2; and

FIG. 7 is a side elevational view thereof from the left of FIG. 2; and,

FIG. 8 is a top, rear and side perspective view thereof. The parts shown in broken line are to illustrate the environment of the present invention and form no part of the claimed design.
